(57) **CLAIM**

The ornamental design of a golf club head, as shown in the accompanying drawings.

DESCRIPTION

FIG. 1 is a perspective view of a golf club head illustrating a contrast of the golf club head of the present design; FIG. 2 is a toe view of a golf club head of the present design; FIG. 3 is a sole view of a golf club head of the present design;

FIG. 4 is a front view of a golf club head of the present design; and,

FIG. 5 is a rear view of a golf club head of the present design.

The broken lines of the golf club head form no part of the invention.
